(57) **CLAIM**

The ornamental design for a transaction card with glowing indicator, as shown and described.

DESCRIPTION

FIG. 1 is a front view of a transaction card with a glowing indicator;

FIG. 2 is a right and left elevational view of FIG. 1; and, FIG. 3 is a top and bottom elevational view of FIG. 1.

The broken lines are for illustrative purposes only and form no part of the claimed design. The radiating lines around portions of the card in FIG. 1 indicate illumination.
